UNITED STATES PATENT OFFICE.

HARRY M. SALYER, OF NEW YORK, N. Y., ASSIGNOR TO LUDWIG & COMPANY, OF NEW YORK, N. Y., A FIRM.

PLAYING ATTACHMENT FOR KEY MUSICAL INSTRUMENTS.

SPECIFICATION forming part of Letters Patent No. 703,743, dated July 1, 1902.

Application filed January 10, 1901. Renewed May 5, 1902. Serial No. 105,975. (No model.)

To all whom it may concern:

Be it known that I, HARRY M. SALYER, a citizen of the United States, and a resident of the city of New York, borough of the Bronx, in the county of New York and State of New York, have invented certain new and useful Improvements in Playing Attachments for Key Musical Instruments, of which the following is a specification.

10 This invention relates to improvements in automatic playing attachments for key musical instruments; and the object of my invention is to provide a new and improved attachment of this kind which is simple in construction, effective in use, and permits of automatically controlling pedals, volumes and intensity of sound, and all such other variations in the playing of a melody that are requisite for properly and fully expressing the composer's musical intentions.

15 In the accompanying drawings, in which like letters of reference indicate like parts in all the figures, Figure 1 is a front elevation of my improved self-playing attachment, parts being in section, some broken away and others omitted. Fig. 2 is an enlarged vertical longitudinal sectional view of the valve for controlling the amount of compressed air admitted into the key-striker-mechanism air-chambers. Fig. 3 is an enlarged vertical sectional view on the line 3 3 of Fig. 1, showing a pneumatic key-striker mechanism and attachments. Fig. 4 is a vertical transverse sectional view on the line 4 4 of Fig. 1, also showing the casing for the attachment in section. Fig. 5 is a plan view of the lever-board. Fig. 6 is an enlarged edge elevation of the note-sheet-reversing gear. Fig. 7 is an enlarged vertical sectional view of one of the controlling-valves for the attachment on the line 7 7 of Fig. 1. Fig. 8 is a front elevation, partly in section, of the reversing-gear. Fig. 9 is a plan view of the same. Fig. 10 is a transverse sectional view through the duct-bridge.

20 The self-playing attachment is provided with a series of pneumatic key-striker mechanisms or analogous mechanisms which are operated by compressed air taken from one or more compressed-air chambers with which 25 said pneumatic striker mechanisms or equivalent mechanisms are connected.

A motor S, preferably operated by compressed air, drives the mechanism for winding a perforated music-sheet or note-sheet *t* from one roller and upon another, which sheet 55 rests upon a bridge provided with ducts which are closed by said sheet except at such times when a hole in the sheet registers with the end of a duct in the bridge. These ducts lead to the several key-striker or other pneumatic 60 mechanisms. The pneumatic striker mechanisms A for the keys are arranged in two or more rows or series, preferably one row for the black keys *a'* and one row for the white keys *a*, and for each row there is a separate 65 compressed-air chamber B. Each striker is pressed upward by a spring A' and can be forced downward by compressed air acting on a diaphragm A² in a suitable casing. Each striker mechanism has a controlling-70 valve A³ for controlling the admission of compressed air from the air-chamber B to the striker mechanism. Adjacent to and parallel with each compressed-air chamber B a chamber B' is located, which several chambers B' 75 are connected by pipes B²⁰ with a suction device or bellows A¹² of any suitable or desired construction for exhausting the air from the chambers B' and other chambers. At each striker mechanism a neck or hub B² extends 80 transversely through the chamber B' and is provided with holes B³, communicating with the chamber B'. In each hub B² a valve-stem B⁴ is guided to move lengthwise, and one end of this stem rests against one face of a dia-85 phragm B⁵, against the opposite face of which the stem A⁴ of the valve A³ rests. The opposite end of the stem B⁴ rests against a dia-90 phragm B⁶, held by a cap B⁷ in a socket B⁸ on the side of the chamber B', which cap has 95 a neck B⁹, from which a tube C extends to a duct D' in the duct-bridge D, over which the perforated note-sheet *t* passes.

When a key-striking mechanism is at rest, the note-sheet closes the duct D' and the air 95 is exhausted from the corresponding tube C, and thus the diaphragm B⁶ is held in equilibrium, as there is the same suction on both faces of it. As soon as the duct D' is opened by the registering of a hole in the note-sheet 100 with the duct atmospheric air passes into the tube C and to the left face of the dia-

phragm B⁶. The suction in the chamber B' acting on this large diaphragm causes a movement to the right, and this takes the valve A³ off the seat. It is true that this suction acts on the diaphragm B⁵ in reverse direction; but as only that small portion of the diaphragm B⁵ at the center of the same corresponding to the diameter of the bore in which the stem B⁴ moves is affected, and this portion is exceedingly small in comparison with the diaphragm B⁶, it does not prevent the movement taking place as described. Likewise the atmospheric pressure on the right-hand side of the diaphragm can only be effective at this small central portion, and hence does not interfere with the above-described movements. When the valve A³ is moved off its seat, the compressed air from the chamber B enters the striker mechanism and forces down the diaphragm A and the striker-rod. Normally the diaphragm B⁶ and the diaphragm B⁵ balance each other, and the suction cannot move the stem B⁴ when the duct C is closed; but when the duct C is open this equilibrium is destroyed and the stem B⁴ is moved to the right. As soon as the corresponding duct D' is closed by the note-sheet t the parts return to their original positions by reason of the confined air being drawn off through the exhaust-vent d into the exhaust-chamber d' in the bridge or tracker-board D. A valve C⁴ is provided in each striker mechanism and is opened by the air-pressure in the chamber B to a degree commensurate with the pressure in said chamber. For the purpose of accentuating any one note by delivering a harder blow by the striker more compressed air must be permitted to pass from the chamber B, and this is accomplished by opening the valve C⁴ to a greater extent. For that purpose the stem of the valve C⁴ is attached to a diaphragm C⁵, on which compressed air can act, which is conducted into the cap C⁶ of said diaphragm through a tube C' from a compressed-air chamber C⁷. These accentuating mechanisms are coupled together and operate in a manner which is shown in general in Fig. 1 for the purpose of general illustration only; but as the details of construction and operation of the accentuating mechanism do not form a part of the invention to be described or claimed in the present application no further description will be given than is necessary to state what they are. Between the partition or wall D² and bridge D⁴ two short shafts E and F are mounted to turn and on their outer ends carry the cog-wheels E' and F' in two vertical parallel planes, as shown in Figs. 8 and 9. The wheel E' is about three times the diameter of the wheel F', so that the rerolling-roller, which is driven by the wheel F', will be rotated about three times as fast as the music-rolling roller, which is driven by the wheel E'.

A shaft F² is driven by bevel-gearing or otherwise from the motor S, and on it a sleeve

F⁴ is mounted to slide lengthwise and to turn with said shaft, which sleeve carries a cog-wheel F⁵, which can engage either the cog-wheel E' or an idle wheel F⁶, according to the position of the sleeve F⁴, which idle wheel engages the wheel F'.

The sleeve F⁴ is provided with an annular groove F⁷ for receiving the forked end G' of a lever G, pivoted at G² to a standard G³, which lever is provided below its pivot with a ring-shaped enlargement G⁴, having two diametrically opposite internal beveled escapement-teeth G⁵, and which teeth can be acted upon by escapement-pins G⁶, arranged in a circle on one face of an escapement-disk H and projecting into the circular enlargement G⁴ of the lever G.

The disk H is fixed on one end of a shaft H', journaled in a suitable support. Said shaft carries a ratchet-wheel H², which is engaged by a pawl H³ on a lever H⁴, mounted to rock on the shaft H' and resting on the upper end of the plunger-rod H⁵ of a pneumatic mechanism H⁶, from which a controlling-tube R⁵ extends to a duct D' in the duct-bridge D, so that every time a hole in the note-sheet registers with this duct the pneumatic mechanism will be operated and the ratchet-wheel H² turned the distance of one tooth.

The lever G is provided at its pivoted end with two opposite arms I and I', which are in contact with the upper ends of the stems of two puppet-valves I² and I³, respectively, which valves are pressed by their springs I¹ upward against seats in the small valve-casings I⁵ and I⁶, having ducts I⁷ I⁸, extending to the outer air, and which ducts can be closed by the valves I² and I³, respectively.

One arm I or I' is raised when the other is lowered, and the valve below the lowered arm is held open while the other is held closed by its spring.

Every time the lever H⁴ is thrown up by the pneumatic mechanism H⁶ the ratchet-wheel H² is turned one tooth and the disk H is turned the distance of one pin G⁶. As a pin G⁶ alternately acts on the two opposite escapement-teeth G⁵, the lever G is alternately thrown in one direction or the other every time the pneumatic mechanism H⁶ is operated.

When the lever G, Fig. 8, is thrown to the right, the cog-wheel F⁵ is engaged with the playing cog-wheel E', and when the lever G is thrown to the left the cog-wheel F⁵ is engaged with the cog-wheel F⁶ and the rewinding cog-wheel F' is operated.

The compressed air, which may be produced by foot-power or by means of a motor of any suitable kind, is stored in the tank J and from the same is conducted by the tube J', part of which is shown in Fig. 4, to a valve-easing J², which is connected by a neck J³ with a similar valve-easing J⁴, this latter easing being connected by a neck J⁵ on its top with a compressed-air chamber J⁶.

Within the easing J⁴ a central hub K is

formed on a horizontal partition K' of this casing, which hub has an annular chamber K^2 open at the top only and in communication with the neck J^3 , leading to the valve-casing J^2 .

A valve K^4 , adapted to rest on and close the top of the hub K has a stem K^5 passing down through the central bore of the hub K and attached at its lower end to a diaphragm K^6 , clamped in the bottom part of the valve-casing J^4 below the horizontal partition K' . That part of the casing J^4 below the diaphragm has a neck K^7 , and a small hole K^8 in the horizontal partition K' establishes communication between the neck J^3 and that part of the casing between said partition and the diaphragm K^6 .

The valve-stem K^5 has a duct K^9 extending upward from its lower end—that is, from below the diaphragm—to the space between the partition K' and diaphragm K^6 , as shown in Fig. 7.

An adjusting-screw K^{10} , extending down into the valve-stem K^5 from the top, serves for adjusting the size of the efficient opening of the duct K^9 .

A tube L , connected with the valve-casing J^4 , is in communication with that part of the casing J^4 above the upper end of the hub K .

The other end of this tube L is connected with a valve-casing L' , which by means of its two apertured necks L^2 is in communication with the two (or more) air-chambers B , Fig. 2.

The casing L' has a transverse partition L^3 , from which a hub L^4 projects, which is provided with an annular chamber L^5 , open at the free end of said hub, and with this annular chamber L^5 the tube L is connected.

The open end of the chamber L^5 can be closed by a valve L^6 , adapted to seat on the end of the hub L^4 and provided with a valve-stem L^7 , extending through the hub and beyond the valve L^6 .

Diaphragms L^8 and L^9 , secured in the casing L' , are attached to opposite ends of the valve-stem L^7 .

A helical spring M is confined between that end of the valve-stem L^7 carrying the diaphragm L^8 and an adjusting-screw M' in one end of the casing L' , and by means of which screw M' the tension of the spring M can be adjusted. A hole N in the partition L^3 establishes communication between the casing L' and the space between the partition L^3 and the diaphragm L^8 .

Beyond the diaphragm L^9 the casing L' has a second transverse partition O , having a central hole O' , which can be closed by a valve O^2 , having its stem O^3 passing through said hole and secured to a diaphragm O^4 , secured in the casing beyond the partition O^9 by a cap O^5 , having a neck O^6 . A tube O^7 extends from the space between the diaphragm O^4 and partition O^2 to the bellows or a suction-tube connected therewith. L^{11} is a vent-hole in the extreme opposite end of the casing L' .

A duct P , formed in the right-hand end of the valve-stem L^7 , connects the compartments at opposite sides of the diaphragm L^9 with each other and can be adjusted in area by means of the screw P' , extending longitudinally through the valve-stem and projecting through and beyond the screw M' , Fig. 2. A tube P^2 extends from the neck O^6 of the cap O^5 to a duct D' in the bridge D .

A tube Q extends from the bottom neck K^7 of the valve-casing J^4 to the casing I^6 , Fig. 8, and a tube Q' extends from this casing I^6 to a cock Q^2 , having a handle-lever Q^3 , and from this cock Q^2 a tube Q^4 extends to the bottom neck of the valve-casing J^2 , Fig. 1.

A tube R , having a cock R' , provided with a handle-lever R^2 , extends from the valve-casing J^2 to the motor S .

A tube R^3 extends from the cock R' to the compressed-air chamber H^9 of the pneumatic mechanism H^6 . A tube R^5 extends from the valve mechanism of the pneumatic mechanism H^6 to a duct D' in the bridge D , and another tube R^6 extends from this valve mechanism to the cock S' , having a spring-pressed handle-lever S^2 , which normally keeps this cock closed.

A pneumatic mechanism T of suitable construction is connected with the compressed-air chamber J^6 , and its plunger-rod or piston-rod T' extends downward and is provided at its lower end with a pad T^2 , which bears on the "forte-pedal" m of the piano.

The rod T' passes through an opening in a fixed bracket T^3 and is pressed upward by a helical spring T^4 , surrounding the rod T' and bearing with its ends on said bracket and on a collar T^5 on said rod. The same mechanism is provided for the "piano" or damping pedal, with the difference that for this pedal the rod T' is provided with a groove or notch T^6 for receiving the end of a spring-pressed latch T^7 , which when the rod T' of the piano-pedal has been forced down by its mechanism automatically locks it in lowered position, as shown in Fig. 1.

A pivoted elbow-lever V can act on the latch T^7 to withdraw the same, thus releasing the piano-pedal-operating rod and permitting its spring to throw it upward. The lever V can be operated at the desired time by means of a pneumatic mechanism V' , which is controlled from the note-sheet by means of an air-tube V^2 , extending to the bridge D .

The music-roll e is removably mounted on one end of the shaft E and a suitable bearing on the partition f' , and the rewinding-roll f is mounted in a similar manner on the shaft F and a bearing on the partition f' . Each duct D' in the bridge D communicates by means of a fine aperture d with a chamber d' , formed in the bridge, and said chamber is connected by a tube d^2 with the vacuum-bellows A^{12} or a tube connected therewith, so as to keep the air rarefied in the said chamber d' . Each aperture d can be adjusted in size by a

screw d^3 , of which one is provided for each duct. Whenever a duct is closed by the music-sheet t after having been opened by the registering of a hole in the sheet with a duct, 5 the air remaining in the duct and the tube leading from the same to a pneumatic mechanism is thus drawn into the chamber d' and from the same by the tube d^2 .

The operation is as follows: I will first describe the operation of some of the parts and then the operation of the entire mechanism. As the compressed air can pass through the hole K^3 in the partition K' of the valve-casing J^4 , Fig. 7, into the space above the diaphragm K^6 and from this space through the duct K^9 into the space below the diaphragm, the pressure on the top and bottom of the diaphragm will be equal as long as the compressed air cannot escape from the space below the diaphragm, and thus the diaphragm is held in equilibrium and the compressed air acting upward on the valve K^4 can lift said valve, permitting compressed air to escape into the space above the valve K^4 and to pass off through the tube L . Whenever communication is established with the outer air by opening the end of the tube Q , connected with the neck K^7 of the valve-casing J^4 , this equilibrium is destroyed, as the compressed air can escape from below the diaphragm K^6 . The pressure on the top of the diaphragm is now much greater than the pressure upward on the valve K^4 , as the diaphragm is much greater in area than the valve. The valve 35 in the casing J^2 operates in the same manner as the valve in the casing J^4 . The spring M in the valve-casing L' , Fig. 2, is set for a certain desired air-pressure in the compressed-air chambers B . As certain parts of a piece 40 of music must be played more forcibly than others, a greater quantity of compressed air must be admitted into the chambers B when such parts are to be played. When the tube P^2 , connected with the neck O^6 of the casing L' , is closed by the note-sheet t , the same air-pressure acts on both sides of the diaphragm L^9 . The diaphragm O^4 normally holds the valve O^3 closed. This air-pressure acting on the diaphragm L^8 compresses the spring M to 45 such an extent as to allow it to hold the valve L^6 open only to such degree as is commensurate with the desired pressure in the chambers B . When a hole in the note-sheet t registers with the tube P^2 , air passes into the chamber 50 at the right of the diaphragm O^4 , Fig. 2, and presses the diaphragm to the left as the air is rarefied between the diaphragm O^4 and the partition O , thereby opening the hole O' and permitting the compressed air in the space between the diaphragm L^9 and the partition O to 55 escape through said hole O' and be carried off by the suction-tube O^7 . The greater pressure on the left-hand side of the diaphragm L^9 now assists the spring M by counteracting the pressure on the diaphragm L^8 and permits the spring M to hold the valve L^6 open to its greatest capacity as long as the valve O^3 is

held open. As soon as the tube P^2 is closed by the note-sheet the valve O^3 is closed, and there will be the same pressure on both sides of the diaphragm L^9 and greater pressure on the right-hand side of the diaphragm L^8 , which acts against the spring M , and thus the valve L^6 is brought back to its normal position and only the normal quantity of compressed air is 70 admitted into the compressed-air chambers B . When the sleeve F^1 , Fig. 8, is in position to roll the music-sheet upon the roller e , the instrument must play and compressed air must be admitted into the chambers B , and, 80 on the other hand, when the note-sheet is being wound back upon the roller f —that is, rerolled—the instrument must not play and no compressed air must be admitted to the chambers B , as this would produce discordant 85 noises. When the sleeve F^1 is in position for winding the note-sheet on the roller e —that is, for playing—the arm I holds the valve I^2 open and permits the spring I^4 of the valve I^3 to hold the same closed, and vice versa. 90 When the note-sheet is being wound on the roller f —that is, rerolled—the arm I' holds the valve I^2 open and permits the spring I^4 to hold the valve I^3 closed. Every time the direction of winding the note-sheet t is changed 95 the positions of the valves I^2 and I^3 must be changed accordingly. The cock Q^2 is normally open, as is also the valve I^2 , and consequently the valve in the casing J^2 is held on its seat and no compressed air can pass 100 into the chambers J^2 J^4 . The valve in the casing J^2 being held on its seat consequent upon the cock Q^2 being normally open is because it is similar to the action upon the valve K^4 in the casing J^4 consequent upon 105 the valve I^3 being open. To start the instrument, the handle-lever Q^3 , Fig. 5, is moved to the left, whereby the cock Q^2 is closed, and thus the valve in the casing J^2 can be raised by the compressed air and compressed air 110 admitted into the casing J^2 , which compressed air passes through the casing J^4 into the tube L and from the same to chambers B . The valve I^3 remains closed, as the sleeve F^1 has not been shifted, and consequently the air 115 passing from the casing J^2 into the casing J^4 can lift the valve K^4 in the casing J^4 . At the same time the motor S is operated by the compressed air passing to the same through the tube R , and the music-sheet or note-sheet t is unwound from the roller f upon the roller e . At the end of the tune a hole in the note-sheet t registers with the duct D' , connected with the tube R^5 , and the pneumatic mechanism H^6 is operated and throws up the lever H^4 , whereby the arms I and I' are so shifted as to open the valve I^3 and close the valve I^2 and to reverse the winding-gear. The closing of the valve I^2 has no effect, as the cock Q^2 is already closed; but by the 120 opening of the valve I^3 the valve K^4 in the casing J^4 is closed, and thus the supply of compressed air to the chambers B is shut off, but not the supply to the motor, which con- 125 130 135

tinues to run until the sheet t is rerolled upon the roller f . Before the end of the sheet is reached a hole in the same again registers with the duct D' , connected with the tube R' , 5 the pneumatic mechanism H^6 is again operated, the winding-gear is reversed and the valve I^3 closed and the valve I^2 opened, and so on alternately until it is desired to stop playing by moving the lever Q^3 to the right, 10 whereby the cock Q^2 is opened. When, then, the end of the tune is reached, the valve I^3 is again opened, the compressed air shut off from the chambers B , and the music-sheet t rewound upon the roller f , and then the pneumatic mechanism H^6 is again operated in the 15 manner set forth by means of the hole provided for that purpose in the end of the sheet, and the parts are brought into the positions shown in Fig. 8—that is, the valve I^3 is closed 20 and at the same instant the valve I^2 is opened. As the cock Q^2 has already been opened during rewinding to stop the instrument, and thus communication established between the outer air and the space below the diaphragms 25 in the casing J^2 , the valve in the casing J^2 is closed as soon as the valve I^2 is opened, and thus the supply of compressed air shut off entirely and the instrument stopped with all parts in position for playing, and the instrument 30 will begin to play as soon as the cock Q^2 is closed again. When it is desired that the music shall be played faster, the cock R' is opened to a greater extent, so as to admit more compressed air to the motor S . If at 35 any time it is desired to stop before a tune is finished and to reroll the sheet t , the spring-pressed lever S^3 is pressed to the right, Fig. 5. Thereby air is admitted into the pneumatic mechanism H^6 and the sleeve F^4 is 40 shifted and the positions of the valves I^2 I^3 changed instantly in the same manner as they would have been changed automatically at the end of the tune, and consequently the sheet is rerolled and all the mechanism 45 stopped, as set forth above.

Having described my invention, what I claim as new, and desire to secure by Letters Patent, is—

1. In a self-playing attachment for musical instruments, the combination with pneumatic playing mechanisms, a duct-bridge and means for moving a music-sheet over the same, of a pneumatic mechanism for reversing the music-sheet-moving gear and at the same time 50 controlling the admission of air to the pneumatic playing mechanisms, substantially as herein shown and described.

2. In a self-playing attachment for musical instruments, the combination with pneumatic 55 playing mechanisms, a duct-bridge and means for moving a music-sheet over the same, of a pneumatic mechanism for reversing the music-sheet-moving gear and at the same time controlling the admission of air to the pneumatic 60 playing mechanisms, and a motor for operating the music-sheet-moving gear, substantially as herein shown and described.

3. In a self-playing attachment for musical instruments, the combination with pneumatic playing mechanisms, a duct-bridge and means 70 for moving a music-sheet over the bridge, of two valve-casings, a valve in each for controlling the admission of compressed air to the pneumatic mechanisms, a tube connected with each casing, a controlling-valve connected with each tube, means for operating said valves so as to keep one open while the other is closed and a pneumatic mechanism for operating said means, substantially as herein 75 shown and described. 80

4. In a self-playing attachment for musical instruments, the combination with pneumatic playing mechanisms, a duct-bridge and means for moving a music-sheet over the bridge, of two valve-casings, a valve in each for controlling the admission of compressed air to the pneumatic mechanisms, a tube connected with each casing, a controlling-valve connected with each tube, means for operating said valves so as to keep one open while the other is closed and a pneumatic mechanism for operating said means and a hand-cock in the tube connected with one of said casings, substantially as herein shown and described. 85 90

5. In a self-playing attachment for musical instruments, the combination with pneumatic playing mechanisms, a duct-bridge and means for moving a music-sheet over the same, of a valve-casing connected with a compressed-air-supply tube, a valve in said casing, pneumatic means for controlling said valve and a pneumatic mechanism for actuating said pneumatic valve-controlling means and the music-sheet-moving means, substantially as 95 herein set forth. 100 105

6. In a self-playing attachment for musical instruments, the combination with pneumatic playing mechanisms, a duct-bridge and means for moving a music-sheet over the same, of a valve-casing connected with a compressed-air-supply tube, a valve in said casing, a second valve-casing, connected with the first-mentioned valve-casing, a valve in said second casing, a pneumatic means in each casing for controlling the valve therein, a pneumatic mechanism for controlling the sheet-moving means and the pneumatic valve-controlling means at the same time, substantially as herein shown and described. 110 115 120

7. In a self-playing attachment for musical instruments, the combination with pneumatic playing mechanisms, a duct-bridge and means for moving a music-sheet over the same, of a valve-casing connected with a compressed-air-supply tube, a valve in said casing, a compressed-air motor, a tube connecting the motor with said valve-casing, a second valve-casing connected with the first-mentioned valve-casing, compressed-air chambers connected with said second valve-casing, a valve 125 in said second casing, a pneumatic means for each casing for controlling the valve therein, and a pneumatic mechanism for controlling the sheet-moving means and the pneumatic 130

valve-controlling means aforesaid, at the same time, substantially as herein shown and described.

8. In a self-playing attachment for musical instruments, the combination with a duct-bridge, and means for moving a music-sheet over the same, of compressed-air chambers, a valve for controlling the admission of compressed air into said chambers, a tube connected with the casing of said valve, a valve at the end of said tube, a cock in said tube and a pneumatic mechanism for controlling the sheet-moving mechanism and the valve at the end of the above-mentioned tube, substantially as herein shown and described.

9. In a self-playing attachment for musical instruments, the combination with a duct-bridge and a means for moving a music-sheet over said bridge, of a pneumatic mechanism for controlling said sheet-moving means, compressed-air chambers, a valve controlling the admission of compressed air into said chambers, means for controlling the said admission-valve by hand, and additional means for controlling the said admission-valve automatically, which automatic means are operated by the pneumatic mechanism controlling the sheet-moving means, substantially as herein shown and described.

10. In a self-playing attachment for musical instruments, the combination with two music-sheet-roller shafts, of gearing for rotating them, a means for throwing either shaft in gear, a pneumatic mechanism for operating the gear-shifting means and means for controlling the supply of motive power to the key-actuating mechanism, by the same pneumatic mechanism that operates the gear-shifting means, substantially as herein shown and described.

11. In a self-playing attachment for musical instruments, the combination with two music-sheet-roller shafts, of gearing for rotating them, a sleeve for throwing either shaft in gear with the driving mechanism, a lever for operating the sleeve, a pneumatic mechanism for operating the lever step by step and a valve for controlling the music-producing mechanism, which valve is also controlled by said lever, substantially as herein shown and described.

12. In a self-playing attachment for musical instruments, the combination with a duct-bridge, of means for moving a music-sheet over

the bridge, a sleeve for throwing said means in gear, a lever for shifting the sleeve, two arms on said lever, a pneumatic mechanism for operating the lever, two valves for controlling the admission of compressed air to various pneumatic mechanisms, a valve for controlling each admission-valve, said controlling-valve having stems in the paths of the arms of the aforesaid lever, substantially as herein shown and described.

13. In a self-playing attachment for musical instruments, the combination with a duct-bridge and means for moving a music-sheet over the same, of compressed-air mechanisms for operating the sound-producing devices and rarefied-air mechanisms for controlling said compressed-air mechanisms from the music-sheet, substantially as herein shown and described.

14. In a self-playing attachment for musical instruments, the combination with a duct-bridge and means for moving a music-sheet over the same, of compressed-air mechanisms for operating the music-producing and other devices, a rarefied-air mechanism, connected with each compressed-air mechanism and ducts extending from said rarefied-air mechanisms to the duct-bridge, substantially as herein shown and described.

15. In a self-playing attachment for musical instruments the combination with a duct-bridge having ducts and a chamber connected with all the ducts, of means for adjusting the connection between each duct and said chamber and means for rarefying the air in said chamber substantially as herein shown and described.

16. In a self-playing attachment for musical instruments the combination with a duct-bridge having ducts, a chamber formed in said bridge and an aperture extending from each duct to said chamber, of a screw at each duct for adjusting the size of the aperture extending from the duct to said chamber and means for rarefying the air in said chamber, substantially as herein shown and described.

Signed at New York city, in the county of New York and State of New York, this 18th day of December, A. D. 1900.

HARRY M. SALYER.
